US0D1105620S

(12) United States Design Patent (10) Patent No.: US D1,105,620 S
(45) Date of Patent: * Dec. 9, 2025

(54) MEMBER FOR COSMETIC COMPACT LID

(71) Applicant: Aekyung Industrial Co., Ltd., Seoul (KR)

(72) Inventor: Nuri Park, Seoul (KR)

(73) Assignee: Aekyung Industrial Co., Ltd., Seoul (KR)

() Term: 15 Years

(21) Appl. No.: 29/900,701

(22) Filed: Aug. 24, 2023

(30) Foreign Application Priority Data

Jul. 19, 2023 (KR) 30-2023-0027877
